United States Patent

Des. 236,661
Patented Sept. 9, 1975

236,661

EYE SHADE

Charles V. Weaver, 18286 Clairmont Drive,
South Bend, Ind. 46637

Filed Mar. 5, 1973, Ser. No. 338,148

Term of patent 14 years

Int. Cl. D2—03

U.S. Cl. D2—247

FIG. 1

FIG. 2

FIG. 3

FIG. 1 is a top plan view of an eye shade showing my new design;

FIG. 2 is a side elevational view thereof; and

FIG. 3 is a rear elevational view thereof.

The opposite side that is represented in FIG. 2 is identical to that shown.

I claim:

The ornamental design for an eye shade, substantially as shown and described.
